SWITCH CONSTRUCTION

Sigurd I. Lindell, Chicago, Ill., assignor to S & C Electric Company, Chicago, Ill., a corporation of Delaware

Application October 31, 1957, Serial No. 693,689

18 Claims. (Cl. 200—162)

This invention relates, generally, to disconnecting switches for electric distribution circuits and it has particular relation to such switches provided with a latch to hold the switch blade against opening movement, with a pull ring for moving the switch blade to the open position and with anchor means to be engaged by an auxiliary interrupter for opening the switch blade under load.

Among the objects of this invention are: To provide a switch blade latch which cannot be activated by a force applied to the blade opening pull ring in order to prevent inadvertent opening of the switch blade while carrying current by means of an ordinary switch stick; to provide for unlatching the switch blade in response to the application of a force by one terminal of an auxiliary circuit interrupter to the conducting anchor means which acts as an anchor during the opening movement of the auxiliary circuit interrupter; to provide a pull ring on the switch blade for receiving the other terminal of the auxiliary circuit interrupter; to space the anchor means and pull ring on the switch relative to the spacing of the terminals of the auxiliary circuit interrupter so that the switch blade is unlatched before operative engagement with the pull ring can be had; to provide a keeper on the switch blade and a cooperating latch hook pivoted on the line terminal carrying the switch contact member; to connect the anchor means to the latch hook for conjoint movement; and to provide the anchor means on opposite sides of the switch blade and integral with the latch hook.

Other objects of this invention will, in part, be obvious and, in part, appear hereinafter.

This invention is disclosed in the embodiment thereof shown in the accompanying drawings and it comprises the features of construction, combination of elements and arrangement of parts that will be exemplified in the construction hereinafter set forth and the scope of the application of which will be indicated in the appended claims.

For a more complete understanding of the nature and scope of this invention reference can be had to the following detailed description, taken together with the accompanying drawings, in which:

Figure 1 is a view, in side elevation, of a disconnecting switch in which the present invention is embodied, the switch being mounted in a vertical position and being arranged for operation through the agency of an auxiliary circuit interrupter of the type illustrated in application Serial No. 569,909, filed March 6, 1956, now Patent No. 2,816,981, issued December 17, 1957, which is shown in the engaged position at the beginning of the switch opening operation with the latch released;

Figure 2 is a view, similar to Figure 1, showing the switch in the partly open position with the auxiliary circuit interrupter extended to a position slightly in advance of the position in which the separable contacts therein are opened to interrupt the shunt circuit bridging the disconnecting switch gap;

Figure 3 is a view, in side elevation, and at an enlarged

2

scale, of the upper portion of the switch blade and a portion of the cooperating upper terminal assembly with the switch blade in the closed and latched position;

Figure 4 is a view, in front elevation, of the portion 5 of the switch construction shown in Figure 3 with the combination guide and anchor member and the latch hook integral therewith swung to the unlatched position to illustrate more clearly the construction;

Figure 5 is a view, in side elevation, of the construction 10 and arrangement shown in Figure 4;

Figure 6 is a view, in front elevation, of the lower portion of the upper terminal assembly and latch, as shown in Figure 4, separate from the switch blade;

Figure 7 is a bottom plan view of the construction and 15 arrangement shown in Figure 6; and

Figure 8 is a sectional view taken generally along the line 8—8 of Figure 6.

Referring now particularly to Figures 1 and 2 of the drawings, it will be observed that the reference character 20 10 designates wood supports or cross arms which are positioned one above the other. It will be understood that they can be positioned in the same horizontal plane. They are arranged for mounting a disconnecting switch assembly, shown generally at 11, which is of the general type illustrated in application Serial No. 638,742, filed February 7, 1957, now abandoned, modified to incorporate the features of this invention. The disconnecting switch assembly 11 can be positioned vertically, as shown in Figures 1 and 2, or it can be mounted in an underhung position as disclosed in the application just referred to.

The disconnecting switch assembly 11 includes a channel base 12 of rolled steel section having a flat side 13 which bears against the respective sides of the wood supports or cross arms 10. As pointed out in the application last referred to, the reason for placing the flat side 13 in the position described is to provide a large area of contact between the channel base 12 and the wood supports or cross arms 10 in order to avoid cutting them 30 as often is the case when the side flanges 14, rather than the flat side 13, are placed in engagement therewith and clamped thereto. The flat side 13 is clamped to the cross arms 10 by means of clamp bolts 15 and clamps 16 which are located on the opposite sides of the wood supports or cross arms 10, as illustrated.

Plates 17 are provided transversely of the side flanges 14 for supporting insulators 18 in spaced relation. The plates 17 can be secured by welding to the side flanges 14 and the insulators 18 can be secured to the plates 50 17 by bolts. At their outer ends the insulators 18 carry upper and lower terminal assemblies 19 and 20. The terminal assemblies 19 and 20 include terminal pads 21 and 22 that are arranged to be connected to line conductors.

The terminal pad 22 of the lower terminal assembly 20 includes an integrally formed outwardly extending hinge member 26 on which is pivoted at 27 a switch blade that is indicated, generally, at 28. At its upper end the switch blade 28 is arranged to engage a contact member 29 which extends outwardly from the terminal pad 21 of the upper terminal assembly 19. Other means can be used for mounting the switch blade 28 for movement toward and away from the contact 29.

It is desirable to provide for moving the switch blade 65 28 toward the open circuit position and out of contact engagement with the contact member 29 while current is flowing therethrough. For this purpose an auxiliary circuit interrupter of the separable contact type, shown generally at 32, is provided. Preferably the auxiliary circuit interrupter 32 is constructed as disclosed in application Serial No. 569,909, filed March 6, 1956, and re-

ferred to hereinbefore. It is arranged to be mounted on a live line insulating stick 33 of the type ordinarily found in a lineman's truck and adapted to have various types of live line tools clamped thereto. At its upper end the live line stick 33 is provided with a metallic fitting 34 for detachable connection to a metallic strut 35. Near its upper end the strut 35 is provided with a laterally extending prong 36 which is arranged to engage a pull ring or eye member 37 that is secured to the switch blade 28 near its swinging end and at a position remote from its hinge end provided by the pivot 27. Movable with the strut 35 and prong 36 is an inner insulating sleeve 38. The sleeve 38 moves within an outer insulating sleeve 39 for the purpose of cocking a spring operating mechanism to effect the separation of the contact members in the auxiliary circuit interrupter 32 in such manner as to interrupt the current flow therewith. Near its upper end the outer insulating sleeve 39 is provided with a conducting part including a bow contact member 40 which constitutes one terminal of the auxiliary circuit interrupter 32 while the other terminal is formed in part by the prong 36. The bow contact member 40 is arranged to be placed over and connected and anchored to a combination guide and anchor member that is shown, generally, at 41 and which is employed, as will be described hereinafter, for unlatching the switch blade 28 to permit it to be swung to the open position.

Referring now particularly to Figures 3 and 4 of the drawings, it will be observed that the switch blade 28 is made up of a pair of elongated switch blade members 44 and that the pull ring or eye member 37, having an opening 37' for receiving the prong 36, is positioned therebetween. The pull ring 37 has an integral boss portion 45 the thickness of which is the same as the spacing between the blade members 44. Rivets 46 extend through the blade members 44 and the boss portion 45 to stationarily mount the pull ring or eye member 37 on the switch blade 28.

As shown more clearly in Figure 7 the combination guide and anchor member 41 includes conducting anchor members or horns 47 which are located on opposite sides of the switch blade 28 and have curved under surfaces 48 for receiving the bow contact member 40 and providing an anchor therefor against which the lineman can exert a pull endwise on the live line stick 33.

In accordance with this invention, provision is made for rockably mounting the combination guide and anchor member 41 which is made up of the conducting anchor members 47. For this purpose a hinge pin 49 is provided on the terminal pad 21 which forms a part of the upper terminal assembly 19. As shown in Figure 6, spaced ears 50 are formed integrally with the terminal pad 21 at its lower end for receiving the hinge pin 49 the ends of which extend into hubs 51 that are integral with the member 41. A torsion spring 52 surrounds the hinge pin 49 and acts to bias the combination guide and anchor member 41 in a clockwise direction as viewed in Figure 5.

Also, formed integrally with the conducting anchor members or horns 47 and centrally thereof is a latch hook 53. As shown in Figures 4 and 8, the latch hook 53 extends forwardly of the terminal pad 21 and is disposed between the switch blade members 44. The latch hook 53 has a shoulder 54 for engaging a detent in the form of a roller 55 which is mounted on a shaft 56 that extends between the blade members 44. When the latch hook 53 occupies the position shown in Figure 3 of the drawings, the shoulder 54 is located in front of the roller 55. Here the shoulder 54 is positioned generally normal to a plane, indicated by a broken line 57, through the axis of the hinge pin 49 and the axis of the shaft 56 on which the roller 55 is mounted and thus opening movement of the switch blade 28 is prevented. An inclined striker surface 58 on the nose portion of the

latch hook 53 automatically deflects the latter when the switch blade 28 is moved to the closed position on engagement by the roller 55. The roller 55 rides over the striker surface 58 and then along the shoulder 54 when the switch blade 28 has been moved to the switch closed position.

Provision is made for limiting the movement of the combined guide and anchor member 41 and the latch hook 53 integral therewith. The upward movement of the latch hook 53, when the switch blade 28 is in the open position, is limited by engagement with a lower end 59 of a stop 60 which depends from the contact member 29. Stops 61 extend outwardly from each side of the upper terminal pad 21, Figures 3 and 4, and cooperate with stop shoulders 62 on the hubs 51 of the combination guide and anchor member 41 to limit its rocking movement in a counterclockwise direction beyond the position shown in Figures 5 and 8.

Particular attention is directed to the arrangement of the combination guide and anchor member 41 with the integral latch hook 53. The conducting anchor members 47 of the member 41 are so spaced from the pivot axis of the hinge pin 49 as to permit operation by application of the live line stick 33 from various angles and to insure that there is a sufficient moment about such axis to move the latch hook 53 to unlatched position and permit subsequent opening of the switch blade 28. It will be noted that the anchor members 47 are offset from the pivot axis of the hinge pin 49 in the direction of the longitudinal axis of the switch blade 28 to provide the proper leverage or movement about this pivot axis even when the live line stick extends at right angles to the switch blade 28. While the arrangement is such that the latch hook 53 rocks toward the pull ring 37, the former can be modified to rock in the opposite direction to unlatch.

There is a preferred relation between the distance 63, Figure 1, between the bow contact member 40 and the prong 36 with respect to the distance 64, Figure 3, between the anchor members or horns 47 and the pull ring or eye member 37. This relationship is such that the bow contact member 40 must engage one or the other of the conducting anchor members or horns 47 and swing the combination guide and anchor member 41 to the position shown in Figures 5 and 8, where the latch hook 53 is in the unlatched position, before the prong 36 can be inserted into the opening 37' of the pull ring or eye member 37. This insures that the switch blade 28 is unlatched to permit opening movement thereof when the auxiliary circuit interrupter 32 has been engaged and further pull is exerted to separate the interrupter contacts to interrupt the circuit after the switch blade 28 has been moved away from the upper terminal assembly 19 to a distance such that there is no likelihood of re-striking of the arc externally of the auxiliary circuit interrupter 32 once it has opened the circuit.

The tension exerted by the torsion spring 52 is so related to the initial tension of the spring in the auxiliary circuit interrupter 32 and to the increased tension of this spring when it is stressed by movement of the inner insulating sleeve 38 out of the outer insulating sleeve 39, that no relative movement, or only a very limited relative movement of the former with respect to the latter, takes place until after the latch hook 53 has been swung to the unlatched position, shown in Figures 5 and 8, where the combination guide and anchor member 41 is prevented from further rotary movement by the stops 61 when they are engaged by the stop shoulders 62. The relation of the spring tensions also is such that no or only limited relative movement of the sleeves 38 and 39 takes place until after the prong 36 has engaged the pull ring 37 and further pull is exerted to swing the switch blade 28 to open position followed by interruption of the current flow by the auxiliary circuit interrupter 32 in the manner described.

Since certain further changes can be made in the foregoing construction and different embodiments of the invention can be made without departing from the spirit and scope thereof, it is intended that all matter shown in the accompanying drawings and described hereinbefore shall be interpreted as illustrative and not in a limiting sense.

What is claimed as new is:

1. A disconnecting switch comprising, in combination, a pair of line terminals in insulated spaced relation having a hinge member carried by one line terminal and a contact member carried by the other line terminal, a switch blade pivoted to said hinge member for movement into and out of engagement with said contact member, a pull ring carried by said switch blade for detachably receiving one terminal of an auxiliary circuit interrupter, latch means on said switch blade and on the other line terminal preventing disengagement of said switch blade from said contact member, conducting anchor means connected to said latch means for receiving another terminal of said auxiliary circuit interrupter, and means mounting said conducting anchor means on said contact member for movement in response to movement of said other terminal of said auxiliary circuit interrupter in the same general direction that said switch blade is moved out of engagement with said contact member to move said latch means to unlatched position whereby force applied by said other terminal of said auxiliary circuit interrupter unlatches said latch means and permits force applied to said pull ring by the one terminal of the auxiliary circuit interrupter to disengage said switch blade from said contact member.

2. A disconnecting switch comprising, in combination, a pair of line terminals in insulated spaced relation having a hinge member carried by one line terminal and a contact member carried by the other line terminal, a switch blade pivoted to said hinge member for movement into and out of engagement with said contact member, a pull ring stationarily mounted on said switch blade near its swinging end for detachably receiving one terminal of an auxiliary circuit interrupter, latch means on said switch blade and on the other line terminal preventing disengagement of said switch blade from said contact member, conducting anchor means connected to said latch means for receiving another terminal of said auxiliary circuit interrupter, and means mounting said conducting anchor means on said contact member for movement in response to movement of said other terminal of said auxiliary circuit interrupter in the same general direction that said switch blade is moved out of engagement with said contact member to move said latch means to unlatched position whereby force applied by said other terminal of said auxiliary circuit interrupter unlatches said latch means and permits force applied to said pull ring by the one terminal of the auxiliary circuit interrupter to disengage said switch blade from said contact member.

3. A disconnecting switch comprising, in combination, a pair of line terminals in insulated spaced relation having a hinge member carried by one line terminal and a contact member carried by the other line terminal, a switch blade pivoted to said hinge member for movement into and out of engagement with said contact member, a pull ring stationarily mounted on said switch blade near its swinging end for detachably receiving one terminal of an auxiliary circuit interrupter, latch means on said switch blade nearer its swinging end than said pull ring and on the other line terminal preventing disengagement of said switch blade from said contact member, conducting anchor means connected to said latch means for receiving another terminal of said auxiliary circuit interrupter, and means mounting said conducting anchor means on said contact member for movement in response to movement of said other terminal of said auxiliary circuit interrupter in the same general direction that said

switch blade is moved out of engagement with said contact member to move said latch means to unlatched position whereby force applied by said other terminal of said auxiliary circuit interrupter unlatches said latch means and permits force applied to said pull ring by the one terminal of the auxiliary circuit interrupter to disengage said switch blade from said contact member.

4. A disconnecting switch comprising, in combination, a pair of line terminals in insulated spaced relation having a hinge member carried by one line terminal and a contact member carried by the other line terminal, a switch blade pivoted to said hinge member for movement into and out of engagement with said contact member, a pull ring carried by said switch blade for detachably receiving one terminal of an auxiliary circuit interrupter, latch means on said switch blade and on the other line terminal normally biased away from the pivot axis of said switch blade to latched position and preventing disengagement of said switch blade from said contact member, conducting anchor means connected to said latch means for receiving another terminal of said auxiliary circuit interrupter, and means mounting said conducting anchor means on said contact member for movement in response to movement of said other terminal of said auxiliary circuit interrupter in the same general direction that said switch blade is moved out of engagement with said contact member to move said latch means to unlatched position whereby force applied by said other terminal of said auxiliary circuit interrupter overcomes the biasing action applied to said latch means and unlatches said latch means and permits force applied to said pull ring by the one terminal of the auxiliary circuit interrupter to disengage said switch blade from said contact member.

5. A disconnecting switch comprising, in combination, a pair of line terminals in insulated spaced relation having a hinge member carried by one line terminal and a contact member carried by the other line terminal, a switch blade pivoted to said hinge member for movement into and out of engagement with said contact member, a pull ring carried by said switch blade for detachably receiving one terminal of an auxiliary circuit interrupter, a keeper carried by said switch blade, a latch movably mounted on said other line terminal and biased away from the pivot axis of said switch blade into engagement with said keeper and preventing disengagement of said switch blade from said contact member, conducting anchor means connected to said latch for receiving another terminal of said auxiliary circuit interrupter, and means mounting said conducting anchor means on said contact member for movement in the same general direction that said switch blade is moved out of engagement with said contact member to move said latch means to unlatched position whereby force applied by said other terminal of said auxiliary circuit interrupter in the general direction that said switch blade is moved out of engagement with said contact member moves said latch out of engagement with said keeper and permits force applied to said pull ring by the one terminal of the auxiliary circuit interrupter to disengage said switch blade from said contact member.

6. A disconnecting switch comprising, in combination, a pair of line terminals in insulated spaced relation having a hinge member carried by one line terminal and a contact member carried by the other line terminal, a switch blade pivoted to said hinge member for movement into and out of engagement with said contact member, a pull ring stationarily mounted on said switch blade remote from its hinge end for detachably receiving one terminal of an auxiliary circuit interrupter, a keeper carried by said switch blade between its swinging end and said pull ring, a latch movably mounted on said other line terminal and biased away from the pivot axis of said switch blade into engagement with said keeper and preventing disengagement of said switch blade from said contact member, conducting anchor means connected to said latch for receiving another terminal of said auxiliary cir-

cuit interrupter, and means mounting said conducting anchor means on said contact member for movement in the same general direction that said switch blade is moved out of engagement with said contact member to move said latch means to unlatched position whereby force applied by said other terminal of said auxiliary circuit interrupter in the general direction that said switch blade is moved out of engagement with said contact member moves said latch out of engagement with said keeper and permits force applied to said pull ring by the one terminal of the auxiliary circuit interrupter to disengage said switch blade from said contact member.

7. A disconnecting switch comprising, in combination, a pair of line terminals in insulated spaced relation having a hinge member carried by one line terminal and a contact member carried by the other line terminal, a switch blade comprising a pair of elongated blade members pivoted to said hinge member for movement into and out of engagement with said contact member, a pull ring between said blade members and secured thereto remote from the hinge end thereof for detachably receiving one terminal of an auxiliary circuit interrupter, a keeper between said blade members and nearer the swinging end thereof than said pull ring, a latch hook pivoted on said other line terminal and extending therefrom between said blade members and between said keeper and said pull ring, spring means biasing said latch hook into engagement with said keeper to prevent disengagement of said switch blade from said contact member, conducting anchor means connected to said latch hook at one side of said switch blade for receiving another terminal of said auxiliary circuit interrupter, and means mounting said conducting anchor means on said contact member for movement in the same general direction that said switch blade is moved out of engagement with said contact member to move said latch means to unlatched position whereby force applied by said other terminal of said auxiliary circuit interrupter in the general direction that said switch blade is moved out of engagement with said contact member moves said latch hook out of engagement with said keeper and permits force applied to said pull ring by the one terminal of the auxiliary circuit interrupter to disengage said switch blade from said contact member.

8. The invention, as set forth in claim 7, wherein the keeper is a roller journaled between the blade members and the latch hook has an inclined striker surface engageable by said roller as said blade members are swung to switch closed position to move said latch hook out of the path of said roller.

9. The invention, as set forth in claim 7, wherein the latch hook and conducting anchor means are of one piece construction.

10. The invention, as set forth in claim 9, wherein the conducting anchor means comprise a pair of anchors disposed on opposite sides of the switch blade with the latch hook being located centrally thereof.

11. The invention, as set forth in claim 10, wherein the latch hook is disposed between the anchors and the pull ring when the switch blade is closed.

12. The invention, as set forth in claim 7, wherein stop means on the other line terminal cooperate with latch hook and conducting anchor means to limit the movement thereof.

13. The invention as set forth in claim 7 wherein the anchor means is spaced from its pivot axis to permit application of the other terminal of the auxiliary circuit interrupter from a relatively wide range of positions in any of which a pull exerted on said anchor means is effective to move the latch hook to unlatched position.

14. The invention as set forth in claim 7 wherein the latch hook is rocked toward the pull ring to unlatched position.

15. A disconnecting switch comprising, in combination, first and second separable switch contact members, a pull

ring carried by said first switch contact member for detachably receiving one terminal of an auxiliary circuit interrupter, latch means on said switch contact members preventing separation thereof, conducting anchor means connected to said latch means for receiving another terminal of said auxiliary circuit interrupter, and means mounting said conducting anchor means on said second switch contact member for movement in the same general direction that said first switch contact member is moved out of engagement with said second contact member to move said latch means to unlatched position whereby force applied by said other terminal of said auxiliary circuit interrupter in the general direction that said first contact member is moved out of engagement with said second contact member unlatches said latch means and permits force applied to said pull ring by the one terminal of the auxiliary circuit interrupter to separate said switch contact members.

16. A disconnecting switch comprising, in combination, first and second separable switch contact members, a pull ring carried by said first switch contact member for detachably receiving one terminal of an auxiliary circuit interrupter, a keeper carried by said first switch contact member, a latch movably mounted on said second switch contact member and biased into engagement with said keeper and preventing disengagement of said switch contact members, conducting anchor means connected to said latch for receiving another terminal of said auxiliary circuit interrupter, and means mounting said conducting anchor means on said second switch contact member for movement in the same general direction that said first switch contact member is moved out of engagement with said second contact member to move said latch means to unlatched position whereby force applied by said other terminal of said auxiliary circuit interrupter in the general direction that said first contact member is moved out of engagement with said second contact member moves said latch out of engagement with said keeper and permits force applied to said pull ring by the one terminal of the auxiliary circuit interrupter to separate said switch contact members.

17. A disconnecting switch comprising, in combination, first and second separable switch contact members, a pull ring secured to said first switch contact member for detachably receiving one terminal of an auxiliary circuit interrupter, a keeper carried by said first switch contact member, a latch hook pivoted on said second switch contact member, spring means biasing said latch hook into engagement with said keeper to prevent disengagement of said switch contact members, conducting anchor means connected to said latch hook for receiving another terminal of said auxiliary circuit interrupter, and means mounting said conducting anchor means on said second switch contact member for movement in the same general direction that said first switch contact member is moved out of engagement with said second contact member to move said latch means to unlatched position whereby force applied by said other terminal of said auxiliary circuit interrupter in the general direction that said first contact member is moved out of engagement with said second contact member moves said latch hook out of engagement with said keeper and permits force applied to said pull ring by the one terminal of the auxiliary circuit interrupter to separate said switch contact members.

18. A disconnecting switch comprising, in combination, first and second separable switch contact members, a pull ring carried by said first switch contact member for detachably receiving one terminal of an auxiliary circuit interrupter, latch means on said switch contacts preventing separation thereof, conducting anchor means connected to said latch means for receiving another terminal of said auxiliary circuit interrupter, and means pivotally mounting said conducting anchor means on said second switch contact member for movement in the same general direction that said first switch contact member is moved out of engagement with said second switch contact member to move said latch means to unlatched position whereby force applied by said other terminal of said auxiliary circuit interrupter in the general direction that said first contact member is moved out of engagement with said second contact member moves said latch hook out of engagement with said keeper and permits force applied to said pull ring by the one terminal of the auxiliary circuit interrupter to separate said switch contact members.

19. A disconnecting switch comprising, in combination, first and second separable switch contact members, a pull ring carried by said first switch contact member for detachably receiving one terminal of an auxiliary circuit interrupter, a keeper carried by said first switch contact member, a latch movably mounted on said second switch contact member and biased into engagement with said keeper and preventing disengagement of said switch contact members, conducting anchor means connected to said latch for receiving another terminal of said auxiliary circuit interrupter, and means mounting said conducting anchor means on said second switch contact member for movement in the same general direction that said first switch contact member is moved out of engagement with said second contact member to move said latch means to unlatched position whereby force applied by said other terminal of said auxiliary circuit interrupter in the general direction that said first contact member is moved out of engagement with said second contact member moves said latch hook out of engagement with said keeper and permits force applied to said pull ring by the one terminal of the auxiliary circuit interrupter to separate said switch contact members.

tion that said first switch contact member is moved out of engagement with said second contact member to move said latch means to unlatched position whereby force applied by said other terminal of said auxiliary circuit interrupter in the general direction that said first contact member is moved out of engagement with said second contact member unlatches said latch means and permits force applied to said pull ring by the one terminal of the auxiliary circuit interrupter to separate said switch contact members, the place of application of said other

terminal of said auxiliary circuit interrupter to said conducting anchor means being spaced from the pivot axis thereof to permit application of said other terminal from a relatively wide range of positions in any of which a pull exerted on said anchor means is effective to unlatch said latch means.
